Another part consists of the design for the side plate S, as distinguished by the deeply-grooved corners t t, bead ornamentation u, and panel-molding v, all shaped and arranged together as particularly shown in the aforesaid engraving, with or without the projections r on the panel. Another part consists of the design for the door W, as distinguished by the panel Q having the projections r thereon, and surrounded by the bead ornamentation x, as shown in the wood-cut, and with or without the imitation strap-hinges y y.
